LUIS G. ABOGADO, OF MEXICO, MEXICO.

PROCESS OF HEATING LIQUIDS.

1,382,157.

Specification of Letters Patent. Patented June 21, 1921.

Application filed May 12, 1919. Serial No. 296,304.

To all whom it may concern:

Be it known that I, LUIS G. ABOGADO, citizen of Mexico, residing at Calle Independencia No. 17, Mexico city, Mexico, have 5 invented certain new and useful Improvements in Processes of Heating Liquids, of which the following is a specification.

This invention relates to a process of heating electrically-conducting liquids, and particularly water, for the purpose of providing a supply of hot liquid, or the heating may be carried, in some cases, to such a point as to vaporize or volatilize the liquid. 10 The object of my invention is to obtain these results with a relatively low consumption of electric current, and in a very short time. To this end, I pass an electric current through a thin spirally-moving film of a conducting liquid, in a direction transverse 15 to the movement of the film, that is to say, across the film. In the preferred forms of my invention, this film is of absolutely uniform thickness, so that the current, which flows across every portion of the film, will 20 exert an equal effect at all points of the film. The liquid forming part of the circuit, the operation will be started by admitting water between the electrodes engaging opposite faces of said film, and when the supply of 25 liquid is shut off, there will be an increased heating effect, so that even if the liquid is simply heated (below its boiling point) during the flow of said film, it will be heated to evaporation when the film becomes 30 stationary, and the steam or vapors evolved will travel in a spiral path, until all the liquid between the electrodes has been vaporized, when the absence of such liquid will 35 break the circuit automatically.

40 The invention will now be described in detail, and its novel features will then be pointed out in the appended claims.

Reference is to be had to the accompanying drawings illustrating three forms of 45 apparatus suitable for carrying out my improved process. Figure 1 is a vertical section, on line 1—1 of Fig. 3, showing one form of such apparatus; Fig. 2 is a vertical section taken on line 2—2 of Fig. 4; Figs. 50 3 and 4 are horizontal sections on lines 3—3 and 4—4 respectively of Figs. 1 and 2. respectively; Fig. 5 is a top view of the bot-

tom head or plug employed in this form of apparatus; Fig. 6 is a top view of the apparatus; Fig. 7 is a vertical central section 55 through the other form of the apparatus, in a plane corresponding to that of Fig. 1; Fig. 8 shows this second apparatus in section on a plane corresponding to that of Fig. 4; and Fig. 9 shows a third form.

60 The apparatus represented in Figs. 1 to 6 inclusive comprises a bottom casing A, which may be of circular cross section, made of metal or other suitable material and provided with an inlet A' which may be screw-threaded as shown for convenient connection with the threaded end of a liquid-supply pipe (not shown), which pipe would be fitted with a cock to regulate and shut off the supply of liquid. On a circumferential 65 internal shoulder A'' of the casing is seated the lower edge of a cylindrical shell B. In the lower portion of said shell is located a lower head or plug C, formed with spaced segmental extensions C' engaging the inner 70 surface of the shell, while the intervening portions of the head are out of contact with the shell, so as to leave two segmental passages D, D', see Fig. 4, in permanent communication with a chamber A* formed in 75 the casing A below the head or plug C. Into the upper end of the shell B is fitted an upper head or plug E, similar to the head C, but having its entire circumference 80 in engagement with the inner surface of the shell. Each of these heads is made with a central aperture through which passes a longitudinal rod F threaded at its ends to receive nuts G, G' fitted into suitable recesses 85 in the outer faces of said heads, the latter 90 being connected by said rod and nuts. The upper end of the shell B fits into a ring H connected, as by screws J, with a cap K provided with an outlet K', which may be 95 connected with a goose-neck pipe L or other means for carrying away the heated liquid, or the steam or vapor produced. The ring H with the cap K corresponds to the casing A, and these parts H, K form an upper casting. The screws J also serve to secure in 100 position, an additional cap M, of insulating material, forming with the cap K a chamber N.

Between the heads C, E, which are made

of insulating material, are located the two electrodes O , O' which are alike in shape, each of them comprising two cylinder segments of different diameters connected by 5 a bend lying in an axial plane, said segments being co-axial with the shell B . Any metal or other suitable conductor (say carbon) may be used for these electrodes. The upper and lower edges of the electrodes are fitted 10 into corresponding grooves in the opposing surfaces of the heads C , E , and the large-diameter portion of one electrode is placed adjacent to the small-diameter portion of the other electrode, so that these portions 15 will be parallel and very close together. The spacing of the overlapping electrode portions is uniform at all points of the electrodes. Between the rod F and the electrodes a tube P , likewise of conducting material, is fitted concentrically, the ends of 20 said tube entering annular grooves in the heads C , E . The cylindrical wall of the tube P is solid, except for perforations such as P' located at its upper portion, adjacent to 25 the head E , and leading from the chamber Q outside the tube to the chamber R within the upper portion of the tube. Apertures E' in the head E connect the chamber R with an outlet chamber S formed between 30 the head E and the cap K . The two bends connecting the cylinder segments of the same electrode are substantially in diametrical alinement, see Fig. 3, and at these bends I secure to the electrodes, as by welding, longitudinal rods T passing through the 35 heads C , E and threaded to receive nuts U , U' . These nuts engage washers V , V' respectively, and insulating sleeves V'' , which might be made integral with the (insulating) washers V' , surround the rods T where 40 they extend through the cap K , which is generally made of metal. The wires W for supplying the current pass through a suitable aperture in the cap or cover M , and 45 their ends are clamped against the nuts U' by binding nuts W' of well-known character, these terminals being contained in the chamber N , and protected by the cap M .

On the threaded portions of the rod F are 50 mounted loosely two disks X the peripheries of which engage the inner surface of the tube P with a sliding fit, and these disks are pressed toward each other by nuts Y , to hold in position a heat-retaining body 55 Z , which is a stone-like mass filling the tube P between said disks; such mass may consist, for instance, of a hydraulic cement made from cement, asbestos, bone ash, and some bichromate of potash to harden the mass.

Through the caps M , K and the upper head E extends a vertical rod a mounted to 60 turn about its axis and carrying at its upper end a handle a' which may also serve as a pointer indicating on a scale M' of the

outer cap M . This rod may extend into the 65 interior of the tube P , and partly into the mass Z , and is always in electrical connection with said tube; the rod a carries a conducting switch-plate b extending through an opening of the tube and adapted to be 70 swung into contact with the electrode O , so that when the switch is in this position, the tube P is electrically connected with said electrode and virtually becomes part of it.

In operation, the electrodes are connected 75 with a source of electricity, generally an ordinary lighting circuit supplying either direct or alternating current, and then the supply of liquid is turned on, so that the water or other liquid will pass through the 80 inlet A' into the chamber A^* , and from there through the segmental passages D , D' into the outer portion of the annular chamber Q , adjacent to the shell B . The liquid will then flow in contact with the outer surfaces of the outer electrode segments, to reach vertical slots c formed between the vertical edge of the outer segment of one electrode and the rod T at the bend of the other electrode. The water then enters the 85 space between the two electrodes O , O' , and forms a film of uniform thickness engaged on opposite faces by the electrodes, said film completing the circuit; that is to say, the circuit remains open until the water or other 90 liquid is in contact with both electrodes. The flow of the water is substantially in a helical or spiral path, being partly circumferential as indicated by the arrows, and partly longitudinal (upward, toward the 95 outlet). When the liquid reaches the free edges of the inner electrode segments, it will pass inwardly through vertical slots d formed between said free edges and the bends of the other electrodes. The liquid 100 thus reaches the space between the inner electrode segments and the tube P , and leaving said space through the perforations P' enters the chamber R and from there passes 105 through the apertures E' to the chamber S and the outlet L . The current passing 110 through the water and through the electrodes heats the water, largely by the heat generated by the passage of the current 115 through the water, and partly by heating the electrodes themselves, which then transfer their heat to the water; a certain portion of this heat may be transferred from the electrodes to the water both before it has reached 120 the film space between the electrodes, and after it has passed into the space between the electrodes and the tube P . It will be noted that in the operation described the cool water is in contact with the inner surface of the shell B , while the hotter water 125 is nearer the center or axis of the apparatus; I thus practically prevent the loss of heat by radiation from the shell. The tem-

perature to which the liquid is heated will depend, of course, on the time it remains in the apparatus, and this is controlled by opening more or less the cock in the water-supply pipe leading to the inlet A'. As the electrodes are very close to each other, and spaced uniformly, a very even and efficient heating action is obtained, and any whirling of the liquid in the space between the electrodes is prevented. The electrodes are of course of different potential at the time the current passes through the liquid between them. Part of the heat developed in the apparatus will be absorbed by the body Z, which thus becomes a heat-reservoir to equalize, or compensate for, any fluctuations in the heating effect which may be due to irregularities in the flow of the liquid or of the current.

Throwing the switch *b* so that it will connect the tube P with one of the electrodes, will virtually increase the surface of that electrode and thereby reduce the internal resistance of the apparatus, so that the amperage of the current is increased. The inside of the shell B might be lined with pitch or other suitable material to prevent rusting or oxidation.

If the supply of water or other liquid is stopped, as by closing the cock in the water-supply pipe, the effect will be at first a moderate rise of the amperage, due to the fact that the water, now being stationary, is heated to a higher temperature, at which its conductivity is greater; this period of increased amperage however is very brief (generally a few seconds), and then follows a period of reduced amperage owing to the fact that the resistance is increasing as the wetted surface of the electrodes is diminished by the evaporation of the liquid. The moderate rise of amperage, for a short time, is not sufficient to burn out the metallic connections of the apparatus. It will be obvious that as there is no renewal and carrying away of the heated water when the supply is shut off, the heating effect will be greater and the boiling point will be reached, reducing the amount of water within the apparatus by evaporation, with a corresponding reduction of the wetted electrode surface and thus a further increase of the heating effect. Finally, when the entire amount of water in contact with the electrodes has evaporated, there will be no electrical connection between the electrodes, and the circuit will thus be broken automatically. The steam or vapor produced after shutting off the supply of liquid, will also travel to the outlet in a spiral path. It will be evident that by a proper regulation of the water-supply cock, the heating effect may be adjusted to obtain at the outlet L either hot water (liquid) or steam (vapor) dur-

ing the time there is a continuous admission of liquid into and (partly) through the apparatus; the steam or vapor, whether produced during the continuous admission of liquid or after shutting off the supply, will travel in a spiral path, as does the liquid at the time it flows between the electrodes. The process may therefore be used for heating liquids to a temperature below the boiling point, or for vaporizing or volatilizing liquids.

In the construction illustrated by Figs. 7 and 8, which is adapted for operation by a three-phase current, there are three electrodes O², O³, O⁴, each of the general step-like arrangement described in connection with the electrodes O, O', but instead of comprising only two segments of different diameters, each of these electrodes O², O³, O⁴ has three segments of different diameters, with intervening bends, forming three sets of vertical slots *c*, *d*, *e*, the three slots of the same set being evenly spaced circumferentially (120° apart), and the outer segment of one electrode overlapping the intermediate segment of the adjacent electrode, which intermediate segment again overlaps the inner segment of another electrode. All these segments are concentric with the axis of the rod F. There are three terminals or binding posts, one for each of the electrodes. In other respects, the construction shown in Figs. 7 and 8 is the same as in Figs. 1 to 6, but no switch such as *b* is shown in Figs. 7 and 8.

In Fig. 9 the shell B' is rectangular instead of cylindrical, and the electrodes O⁵, O⁶ are given a corresponding shape. They too consist of portions of a segmental nature arranged to overlap and to form a spiral path for the thin film of liquid traveling between the electrodes, the opposing, film-engaging faces of the electrodes being evenly spaced at all points of the film, in each form of my invention.

In other respects, the forms of my invention illustrated by Figs. 7, 8, and 9 are constructed in substantially the same manner as the form shown in Figs. 1 to 6, and the operation and advantages of all three forms of apparatus are practically the same.

Various modifications may be made without departing from the nature of my invention as set forth in the appended claims.

I claim as my invention:

1. The process which consists in passing an electric current across every portion of a non-whirling film of a conducting liquid moving spirally and helically at a substantially constant speed.

2. The process which consists in forming a conducting liquid into a spirally and helically moving film of constant thickness throughout its path so as to secure a sub-

stantially constant speed of flow, and passing an electric current across said film, at every portion thereof, while the film is in spiral and helical motion.

5 8. The process which consists in causing a conducting liquid to travel spirally and helically in a thin film and passing an electric current across said moving film to heat

the liquid, then stopping the flow of the liquid and passing an electric current 10 through the liquid while the latter is stationary, to heat the liquid to a higher temperature, and removing the resulting vapors in a spiral and helical path.

LUIS G. ABOGADO
